MODULAR RESTAURANT

Harry P. Calevas, 2800 E. Sunrise Blvd.,
Fort Lauderdale, Fla. 33304

Continuation-in-part of design application Ser. No.
24,856, Sept. 4, 1970. This application July 16,
1971, Ser. No. 163,554

Term of patent 14 years

Int. Cl. D25—03

U.S. Cl. D13—1

FIG. 1

FIG. 2

FIG. 3

FIG. 4

FIG. 5

FIG. 6

FIG. 7

FIG. 8

FIG. 9

FIG. 1 is a view of a modular restaurant interior in accordance with my design;

FIG. 2 is a sectional view taken along line 2—2 of FIG. 1 looking at a serving line;

FIG. 3 is a sectional view taken along line 3—3 of FIG. 1 looking at cashier and pickup stations;

FIG. 4 is a sectional view taken along line 4—4 of FIG. 1 looking at the rear side of the cashier and pickup stations;

FIG. 5 is a sectional view taken along line 5—5 of FIG. 1 looking at a work and storage area;

FIG. 6 is a front elevational view of the exterior of the modular restaurant;

FIG. 7 is a rear elevational view of the exterior of the modular restaurant;

FIG. 8 is an elevational view of one end of the restaurant; and

FIG. 9 is an elevational view of the other end of the restaurant.

The seats and tables shown in the island at center right of FIG. 1 and along the wall below and to the right of the island are of plain design.

This application is a continuation-in-part of application Ser. No. D. 24,856, filed Sept. 4, 1970 and now abandoned.

I claim:

The ornamental design for a modular restaurant, as shown and described.
